CLAIM

The ornamental design for a tie down bracket for luggage rack, as shown and described.

DESCRIPTION

FIG. 1 is a front elevational view of a tie down bracket for luggage rack showing our new design;
FIG. 2 is a side elevational view thereof;
FIG. 3 is a rear elevational view thereof;
FIG. 4 is a side elevational view thereof from the side opposite that of FIG. 2;
FIG. 5 is a top plan view thereof, and
FIG. 6 is a bottom plan view thereof.
